US00D834086S

(12) **United States Design Patent** (10) **Patent No.:** **US D834,086 S**
Chandrasekhar et al. (45) **Date of Patent:** **** Nov. 20, 2018**

(54) **ELECTROCHROMIC EYEWEAR**

(71) Applicant: **Ashwin-Ushas Corporation, Inc.**,
 Holmdel, NJ (US)

(72) Inventors: **Prasanna Chandrasekhar**, Holmdel,
 NJ (US); **Brian J. Zay**, Hamilton, NJ
 (US); **Edward J. Laganis**, Hoboken,
 NJ (US); **Vasily V. Romanov**, Jersey
 City, NJ (US); **Anthony J. LaRosa**,
 Rockaway, NJ (US)

(73) Assignee: **Ashwin-Ushas Corporation, Inc.**,
 Holmdel, NJ (US)

(**) Term: **15 Years**

(21) Appl. No.: **29/530,355**

(22) Filed: **Jun. 16, 2015**

(51) LOC (11) Cl. **16-06**

(52) U.S. Cl. **D16/309**
 USPC

(57) **CLAIM**

The ornamental design for an electrochromic eyewear, as shown and described.

DESCRIPTION

FIG. 1 is a left front perspective view of electrochromic eyewear showing our new design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken lines are included for the purpose of illustrating unclaimed portions of the electrochromic eyewear that form no part of the claimed design.

1 Claim, 5 Drawing Sheets
